UNITED STATES PATENT OFFICE.

JOHN E. MILLER, OF WASHINGTON, PENNSYLVANIA, ASSIGNOR TO THE DUNCAN AND MILLER GLASS COMPANY, OF WASHINGTON, PENNSYLVANIA, A CORPORATION OF PENNSYLVANIA.

DESIGN FOR A GLASS DISH.

SPECIFICATION forming part of Design No. 37,188, dated October 18, 1904.

Application filed September 20, 1904. Serial No. 225,267. Term of patent 3½ years.

To all whom it may concern:

Be it known that I, JOHN E. MILLER, of Washington, Washington county, Pennsylvania, have invented a new, original, and ornamental Design for Glass Dishes, reference being had to the accompanying drawings, forming part of this specification, in which—

Figure 1 is a bottom plan view showing a dish embodying my design; and Fig. 2 is a side elevation of the same, partly in section.

I claim—
The ornamental design for a glass dish, as shown.

J. E. MILLER.
